R. W. HUBBARD

VEHICLE HINGE

Filed Nov. 12, 1923

INVENTOR.

R. W. Hubbard
BY
James J. Sheehy, ATTORNEY S.

UNITED STATES PATENT OFFICE.

RICHARD W. HUBBARD, OF ASHTABULA, OHIO.

VEHICLE HINGE.

Application filed November 12, 1923. Serial No. 674,270.

To all whom it may concern:

Be it known that I, RICHARD W. HUBBARD, a citizen of the United States, residing at Ashtabula, in the county of Ashtabula and 5 State of Ohio, have invented new and useful Improvements in Vehicle Hinges, of which the following is a specification.

My present invention pertains to concealed hinges for motor vehicles and the like and it contemplates the provision of a hinge that is so constructed and arranged that it may be easily applied to the vehicle and the door to which the hinge is secured may be removed from the door casing without the necessity of displacing the elements that are secured either to the door or casing.

The invention further contemplates the provision of a simple and inexpensive hinge that when adjusted produces a concealed hinge and this notwithstanding the fact that positioning of the door relative to the casing may be accomplished by a person whether skilled or unskilled in the art of door-hanging.

Another object of the invention is the provision of a hinge that is so constructed and arranged that it may be moved to a position to permit of the painting of the door and casing without the necessity of removing the door from the vehicle body.

Other objects and characteristic advantages of the invention will be fully understood from the following description and claims when the same are read in connection with the drawings forming part of this specification, in which—

Figure 1 is a vertical sectional view of the elements comprising my invention and showing the same as applied to a door and door frame of a vehicle.

Figure 2 is a view taken in the plane indicated by the line 2—2 of Figure 1, and looking in the direction of the arrow.

Figure 3 is a similar view but showing the door in its open position.

Figure 4 is a rear elevation of my novel hinge per se.

Figure 5 is an edge elevation of the hinge.

Figure 6 is a view taken in the plane indicated by the line 6—6 of Figure 5 and looking in the direction of the arrow.

Figure 7 is a view taken in the plane indicated by the line 7—7 of Figure 6 and looking in the direction of the arrow.

Similar numerals of reference designate

corresponding parts in all the views of the drawings.

The door of a vehicle or the like is indicated by the numeral D whereas the frame is indicated by the numeral F and adapted to be secured to the frame F is the leaf 1 that is provided with openings 2 for fastening means.

The leaf 1 is provided with the right angle portion 3 and arranged in the right angle portion 3 is a slot 4. This slot is for an important purpose hereinafter set forth. Arranged at the end of the right angle portion of the hinge opposite the slotted portion 4, is a hinge 5 and at this point, I would have it understood that the hinge is so constructed that it comprises two ears as shown that rest between the ears 7 of the plate 8 of the hinge and a pintle 6 passes through the upper ear 7 then through the portions 5 of the leaf 1 and hence it will be seen that when the pintle is properly positioned the hinged portion will comprise five elements that are secured to each other and manifestly the possibility of getting the hinge out of line is precluded and at the same time reinforcement of the hinge at its weakest point is materially effected.

Extending and forming a continuation of the plate 8 is a circular portion 9 having upper and lower flanges 10 while at its end the circular portion 9 is provided with the lips 11. This bent or circular portion 9 is adapted to travel during opening and closing of the door through the slot of the bent portion 3 as clearly shown in Figure 3 and the bent portion 9 is also provided with an aperture for an important purpose hereinafter set forth.

Adapted to be secured to the door by means of fasteners that pass through the apertures 17 is a leaf 16. This leaf is provided with a bent portion 12 that in turn is provided with the apertures 13 and 14 and the bent portion 12 is further constructed so as to enter the lips 11 of the bent portion 9. By means of the set screw 15 the two portions may be removably secured to each other by passing said set screw into the aperture in the male bent portion 12 and the female portion 9. The holding of the door in its proper working position is accomplished by forcing the male portion 12 to its extreme limit of travel and then passing the set screw so

that it rests in the aperture or opening 13. If it is desired however, to hold the door away from the frame without entirely disconnecting the leaves from each other the set screw is removed and the male portion 12 is pulled until its aperture 14 registers with the aperture of the female portion 9 when it will be retained in such position by inserting the set screw 15 again.

10 It will be apparent from the foregoing that skilled labor is not required in order to hang a door equipped with the hinge at hand but a person who is able to use in any degree a screw driver may first attach the frame portion of the hinge in position and the door portion of the hinge at the proper point on the door and then merely force the male portion into the female portion when perfect hanging of the door will be 20 assured.

The invention is inexpensive to produce but notwithstanding this fact the hinge is reinforced at the points where experience has taught hinges are generally weak.

25 Having described my invention, what I claim and desire to secure by Letters Patent is:—

30 1. As an article of manufacture, the combination of a leaf having portions arranged at right angles to each other; one of which portions is provided with a bowed surface and with a substantially oblong aperture in the center thereof; and the other of the angular portions having pintle receiving 35 apertures on the end thereof, an angular plate having one of its portions bowed, ears formed on the angular plate adjacent the arc portion thereof, pintle engaging mem-

bers arranged on one end of the plate; the arced portion of the angular plate having bent side edges and also having apertures therein, a second leaf having an integral angular portion adapted to enter the bent edges of the bowed surface of the first angular portion and further adapted to be 45 engaged in detachable manner with respect to the bowed portion of the first angular member.

2. As an article of manufacture the combination of a leaf having an elongated slot therein, a member having portions that are arranged at substantially right angles to each other; one of said portions being bowed and being hinged to the leaf; whereby a portion of the member may move into and out of the slot, guide-ways formed on the member and apertures arranged therein, a second leaf having an angular portion that enters the guide-ways and is adapted to be secured on the member of the first leaf.

3. As an article of manufacture the combination of a leaf, a bowed member formed on the leaf and having apertures therein, a second leaf having an opening therein, a member hinged to the second leaf, and means arranged on the bowed member for engaging in a removable manner the member of the first leaf.

In testimony whereof I have hereunto 70 set my hand in presence of two subscribing witnesses.

RICHARD W. HUBBARD.
